(57) **CLAIM**

We claim the ornamental design for a medicine container, as shown and described.

DESCRIPTION

FIG. 1 is a first perspective view of a first embodiment of a medicine container showing our new design;

FIG. 2 is a second perspective view thereof;

FIG. 3 is a front view thereof;

FIG. 4 is a side view thereof;

FIG. 5 is a rear view thereof;

FIG. 6 is a side view of the opposite side of FIG. 4;

FIG. 7 is a top view thereof;

FIG. 8 is a bottom view thereof;

FIG. 9 is a first perspective view of a second embodiment of a medicine container showing our new design;

FIG. 10 is a second perspective view thereof;

FIG. 11 is a front view thereof;

FIG. 12 is a side view thereof;

FIG. 13 is a rear view thereof;

FIG. 14 is a side view of the opposite side of FIG. 12;

FIG. 15 is a top view thereof; and,

FIG. 16 is a bottom view thereof.

(Continued)

The broken lines shown in the drawings illustrate portions of a medicine container that form no part of the claimed design.
